SPECIMEN SUPPORTING DEVICE

David C. Scott, Providence, R. I., assignor to
Henry L. Scott Company, a corporation of
Rhode Island

Application January 26, 1932, Serial No. 588,964

8 Claims. (Cl. 73—51)

This invention relates to a specimen supporting and clamping device for a testing machine particularly the type illustrated in the co-pending application, Serial No. 193,481, filed May 23, 5 1927 which has matured in Patent No. 1,878,193 dated September 20, 1932, of which I am one of the joint inventors, and has for its object to provide an arrangement by which the specimen may be positioned in the machine without distortion 10 thereof.

Another object of this invention is the provision of means for engaging and supporting the specimen which may be removed from the machine to permit the specimen to be positioned 15 thereon without distortion and then mounted in the machine, thus avoiding pulling the specimen or sample into the machine with likelihood of distortion.

Another object of this invention is the provision of quick clamping means for securing the specimen mounted between the separable supporting members in position in the machine.

A further object of the invention is the provision of a clamping means which upon release 20 will be removed from clamping position.

A still further object of the invention is the provision of guide means to more accurately direct the movement of the relatively movable head members, one of which supports the specimen and the other of which supports the device 25 to apply pressure to the specimen.

With these and other objects and advantageous features in view, the invention consists of a novel arrangement of parts more fully disclosed in the 30 detailed description following, in conjunction with the accompanying drawing, and more particularly set forth in the appended claims.

In the drawing:

Fig. 1 is a front elevation of the relatively 35 movable head members of a ball bursting testing machine, such as disclosed in the above mentioned patent application, with my improved features mounted thereon;

Fig. 2 is a central sectional view on line 2—2 of 40 Figure 1;

Fig. 3 is a sectional view through the holding plates for the specimen which is removable from the machine;

Fig. 4 is a view similar to Figure 3 with the 45 plates in binding position on the specimen;

Fig. 5 is a face view of the inner surface of one of the plates;

Fig. 6 is a face view of the inner surface of the other of the plates.

50 It is found in the use of a burst testing machine

such as disclosed in the above mentioned application, that in placing sheer specimens between the clamping members that they are often pulled and distorted so that in the use of specimens the warp and weft threads are at various angles to 5 one another rather than at right angles as produced in the finished specimen, which will affect the accuracy of the test applied to the specimen; and in order to avoid this result, I have provided removable plates between which a specimen such as fabric to be tested may be mounted by merely laying the specimen on one of the plates and then positioning the other plate thereon, after which the plates with the specimen between them are positioned in the machine for 10 the test which eliminates the possibility of distortion by pulling the specimen into the machine; also, I have provided a quick acting clamping arrangement operated by a cam against a coil spring by which the plates are securely held in 15 position, and which when released will rise by means of the spring to permit the plates to be quickly removed for insertion of another specimen; and I have further found that I may elongate the tubular support for the ball which applies pressure to the specimen and utilize this 20 elongated support as a guide to centralize the relatively moving heads and provide for more accurate movement thereof; and the following is a detailed description of the present embodiment 25 of this invention, illustrating the preferred means by which these advantageous results may be accomplished.

With reference to the drawing, 10 designates 30 the cross bar of the relatively stationary head member which is provided with upright guide rods 11 secured together by an upper cross bar 12 and from which an upright tubular support 13 extends provided with a ball or sphere 14 at the top for applying pressure to the specimen. 35 The relatively movable head member consists of a lower cross bar 15 from which extend upwardly guide rods 16 through openings in the cross bar 10 and which have mounted on their upper ends a U-shaped member 17 guided by means of 40 suitable openings in the ear portions 18 thereof upon the guide rods 11. This member is provided with a deck plate 19 having an opening 20 therein and a recess 21 surrounding the opening 45 to receive a pair of clamp plate members 22 and 23 between which the specimen or fabric 24 to be tested is positioned.

The plate members are circular in shape, being provided with an opening 25 also circular, forming the same annular in shape. The inner sur- 50 55

faces of each of the members are corrugated as at 26 to provide a better frictional gripping surface of the specimen 24, and these members are provided with centering means consisting of a 5 V-shaped annular groove 27 in the member 23 and a plurality of conical or pointed pins 28 in the member 22 to extend into this V-shaped groove to center the plates one with reference to the other and cause their openings 25 to 10 register.

In use, one of the plates is laid upon a suitable support and the specimen is laid upon the plate, whereupon the other plate is then laid over the specimen and the same is thus held without possible distortion from pulling, after which the two plates held together by the hand of the operator are placed on the deck plate 19 in the groove 21 and are clamped on the deck plate by a yoke 29 forced downwardly through the rod 30 by means 15 of the cam 31 operated by handle 32 engaging the abutting head 33 thereof. A spring 34 engages beneath the abutment head 33 and acts between the same, and the abutment 35 on the brace member 36 of the U frame 17 tending to 20 force the rod 30 and the yoke 29 carried thereby upwardly. The position of the yoke on the rod 30 may be adjusted by means of the set nuts 37 and 38 engaging the threaded portion 39 of this rod on either side of the portion 40 of the yoke head. 25

30 In order that the relative movements of the heads may be further guided than by the upright rods, arms 41 extend from the deck plate 19, and are provided with rolls or disks 42 to engage the elongated support 13 in a plurality 35 of points three, four or more about the same to centrally guide the relative movements of the head and assist the guiding action of the rods 11 and 16 which slide through portions thereof, as above mentioned.

40 While I have described certain construction forms which embody the principles of my invention, it is obvious that other desired changes in arrangement may be made within the spirit and the scope of the invention as defined in the 45 appended claims.

I claim:

1. A specimen supporting device for a testing machine comprising two relatively movable head members, one of which receives the specimen sheet to be tested, and the other of which is provided with pressure applying means to engage the specimen comprising an elongated support extending at right angles to the plane of the specimen sheet as received by said specimen receiving head member, and means provided on the specimen receiving head member for engaging said support and guiding the relative movement of said head members. 50

60 2. A specimen supporting device for a testing machine comprising two relatively movable head members, one of which receives the specimen to be tested, and the other of which is provided with pressure applying means to engage the specimen comprising an elongated tubular support extending centrally thereof, and a plurality of arms on the specimen receiving head member, each arm being provided with a roll to engage said support and assist in guiding the relative movement of said head members. 65

70 3. A specimen supporting device for a testing machine comprising two relatively movable head members, one of which receives the specimen to

be tested, a deck plate on said last-mentioned head member having an opening therethrough, a pair of removable specimen clamp members on said plate having registering openings therein, means carried by the clamp members for centering said clamp members with reference to each other, means for centering said members with reference to said deck plate opening, and means on said head member to secure the clamp members in position. 10

4. A specimen supporting device for a testing machine comprising two relatively movable head members, one of which receives the specimen to be tested, a deck plate on said last-mentioned head member having an opening therethrough, 15 a recess about said opening, a pair of removable specimen clamp plates fitting in said recess, means on said head member to secure the clamp plates in position, and means for centering said clamp plates with reference to each other comprising 20 recess means on one of said clamp plates, and projections on the other clamp plate to extend thereinto.

5. A specimen supporting device for a testing machine comprising two relatively movable head 25 members, one of which receives the specimen to be tested, a deck plate on said last-mentioned head member having an opening therethrough, a pair of removable specimen clamp members on said plate having registering openings therein, 30 means carried by the clamp members for centering said clamp members with reference to each other, a yoke member, means for guiding said yoke member toward and from said deck plate, and reciprocating means for moving said yoke 35 member toward said plate.

6. A specimen supporting device for a testing machine comprising two relatively movable head members, one of which receives the specimen to be tested, a deck plate on said last-mentioned head member having an opening therethrough, a pair of removable specimen clamp members on said plate having registering openings therein, means carried by the clamp members for centering said clamp members with reference to each other, a yoke member, means for guiding said yoke member toward and from said deck plate, a spring 40 for raising said yoke member, and cam means for moving said yoke member toward said plate for binding action. 45

7. A specimen supporting device for a testing machine comprising two relatively movable head members, one of which receives the specimen sheet to be tested, and the other of which is provided with pressure-applying means to engage the specimen comprising an elongated support extending at right angles to the plane of the specimen sheet as received by said specimen receiving head member, and means for engaging said support and guiding the relative movement 55 of said head members.

8. A specimen supporting device for a testing machine comprising a member provided with a deck plate having an opening therethrough, a pair of removable specimen clamp members on said plate having registering openings therein, means carried by the clamp members for centering said clamp members with reference to each other, means for centering said members with reference to said deck plate opening, and means for securing the clamp members in position. 65
